UNITED STATES PATENT OFFICE.

MAX HERSKOVITZ, OF CHICAGO, ILLINOIS, ASSIGNOR TO PEERLESS LIGHT COMPANY,
OF CHICAGO, ILLINOIS, A CORPORATION OF MAINE.

ELECTRIC-LAMP-SUPPORTING STRUCTURE.

Application filed January 21, 1922. Serial No. 530,824.

To all whom it may concern:

Be it known that I, MAX HERSKOVITZ, a citizen of the United States, residing at Chicago, in the county of Cook and State 5 of Illinois, have invented a new and useful Improvement in Electric-Lamp-Supporting Structures, of which the following is a specification.

My invention relates more particularly, 10 though not exclusively, to electric-socket-supporting structures of the type which are supported from a base, as is common with table or floor lamps. One of my objects is to provide for the supporting of the electric- 15 bulb-receiving sockets in a manner to permit the sockets to be adjusted into different positions relative to the part which supports them, preferably to cause the bulbs carried thereby to extend downwardly or in 20 either direction in a substantially horizontal plane. Other objects are to provide a novel, simple, substantial and inexpensive construction by which the positioning of the bulbs as stated may be accomplished; to 25 provide a new and improved form of combined housing for the electric wires and support for the socket or sockets, and preferably also for switch mechanism controlling the supplying of current to the bulbs, 30 which shall be strong and durable and may be used in a variety of locations and used with either of its wire-receiving tubular portions uppermost; to provide a plural socket construction of the type above referred to which will permit of the wiring 35 connecting the socket-interiors, and the switch where such is provided for enclosure in the casing, being wired before assembly with the housing structure; and 40 other objects as will be manifest from the following description.

Referring to the accompanying drawings:

Figure 1 is a view in elevation of the upper end of a socket-supporting structure 45 provided with a plurality of bulb-receiving sockets, and embodying my invention, showing the sockets in a position in which the bulbs supported therein, and shown by dotted lines, assume a depending position. Figure 2 is a similar view showing the bulb-receiving sockets extending in substantially 50 horizontal position but in opposite directions, one of the cap plates at this side of the structure being removed to show interior 55 details. Figure 3 is a perspective view of a

fibre cup employed. Figure 4 is a plan sectional view of the structure, the section being taken at the line 4 on Fig. 2 and viewed in the direction of the arrow. Figure 5 is a view in side elevation of a boss-equipped 60 ring-shaped member forming a part of the structure of Figs. 1 and 2. Figure 6 is a face view of one of the two similar hollow caps which cooperate with the structure shown in Fig. 5 to form therewith the central housing member of the structure, the cap being viewed from its inner side. Figure 7 is an end view of a switch device located within the housing of Figs. 5 and 6 together with the wires which lead therefrom to the contacts of the bulb-receiving 65 sockets. Figure 8 is a view like Fig. 5 of the structure therein shown, but viewing it from the opposite side thereof. Figure 9 is an edge view of the structure of Figs. 5 and 8. Figure 10 is a view like Fig. 7 and of the structure shown therein, but viewing it from the end opposite that shown in this figure, and showing in addition the bulb-receiving sockets partly broken away and 70 connected with the wires leading to the switch device. Figure 11 is a plan view of the structure of Figs. 1, 2 and 4, with certain of the parts shown in section. Figure 12 is a section taken at the line 12 on Fig. 11 and viewed in the direction of the arrow. Figure 13 is a view like Fig. 1, of a modification of the structure shown in the preceding figures. Figure 14 is a plan sectional view of the structure shown in Fig. 13, the section being taken at the line 14 on Fig. 13 and viewed in the direction of the arrow. Figure 15 is a bottom plan view of the upper section of the wire housing and socket-supporting member of the structure. Figure 16 is a plan view of the lower section of the housing. Figure 17 is a view in sectional elevation of the housing; and Figure 18, a section taken at the line 18 on Fig. 13 and viewed in the direction of the arrow.

Referring more particularly to the structure illustrated in Figs. 1 to 12 inclusive, wherein my invention is embodied in an electric-socket-supporting structure of the type involving a base (not shown) at which the structure is adapted to be supported, as for example on a table or a floor, with a standard rising therefrom and supporting adjacent its upper end, the upright, or standard, portion, which is shown as formed 105 110

of a tube, is represented at 19, this tube not only serving as a support but also serving to enclose the electric-current conducting wires which lead to the bulb-receiving sockets hereinafter referred to. The upper end of the tubular upright 19 is secured to a housing member represented generally at 20, as by screwing the member 19 into the hollow depending boss portion 21 of the housing 20. This boss member 21 is provided as a part of a ring-shaped member 22 which is formed, preferably integrally, with an upwardly-extending boss 23 preferably in vertical alignment with the boss 21. The housing portion 20 also comprises cap plates 24 and 25 of general dish shape as shown, preferably of semi-spherical form, which are adapted to be assembled with the ring-shaped member 22 at the opposite ends of the opening therethrough, in a manner hereinafter described, to complete the housing and cause the latter to be of substantially spherical form as shown, the cap-plates 24 and 25 being each provided with diametrically-opposed outwardly-extending lugs 26 at their open sides. The ring member 22 is preferably provided at opposite faces with annular flanges 27 with which the cap plates 24 and 25 telescope when the latter are applied to the member 22. The ring member 22 is also provided with diametrically-opposed bosses 28 and 29 which preferably extend horizontally, these bosses being of cylindrical shape and formed about their peripheries, immediate their ends, with circumferentially-extending grooves 30 extending throughout a portion only of the circumference of the bosses 28 and 29 affording shoulders 31 and 32 at the ends of these grooves. The bosses 28 and 29 are hollow, as represented more particularly in Fig. 8, the passages therethrough and represented at 33 opening into the interior of the ring member 22, and the outer surfaces of these bosses at one face of the ring member 22 from the adjacent flange 27 to the grooves 30, containing recesses 34 which extend lengthwise of these bosses throughout the length of the latter and open into the interior of the member 22. The bosses 28 and 29 at points diametrically opposed to the recesses 33, are cut away from their outer extremities to the inside of the ring member 22, as represented at 35. When the cap sections 24 and 25 are applied to position at opposite sides of the ring member 22 as shown in Figs. 4 and 11, the recesses 34 and 35 receive the lugs 26 of the caps which become positioned on the ring member 22 as disclosed in the drawings, more particularly Figs. 4 and 11. The bulb-receiving sockets of the structure are represented at 36, these sockets being formed with hollow shells 37 provided with laterally-extending hollow portions 38 opening into the interiors of the shells 37 and

containing bores 39 of circular shape in cross-section adapting these sockets to be telescoped at their portions 38, with the bosses 28 and 29 as shown in Fig. 11, these socket portions when assembled with the ring member 22 overlapping the lugs 26 of the caps 24 and 25 and holding the latter in place on the ring member 22. The portions 38 are equipped with set-screws 41 which extend at their inner ends, as represented of the one in Fig. 12, into the circumferential grooves 30 in the bosses 28 and 29, thereby holding these socket members 36 against accidental disengagement from the housing member of which the ring 22 is a part, 70 while permitting of the independent rotation of the socket members on this housing except as limited by the stops 31 and 32 which are provided primarily to prevent undue twisting of the electric-current-conducting wires extending into the sockets. 75

The socket members 37 contain socket interiors (not shown), in accordance with common practice, these socket interiors being of any suitable construction and affording contacts for the lamp and, as shown, being formed with an outer screw-threaded contact 42 and a center contact 43. The wires (not shown) leading into the housing 20, for conducting current to the sockets, are connected with a terminal block represented at 44 which may be of any suitable construction adapting of the connection of the lead wires thereto as represented at 45 and 46, the various wires represented at 47, 48, 49 and 50 and extending through the bosses 38 and electrically connected with the contacts of the socket interiors referred to, being connected at the block 44 with the terminals 45 and 46 in a manner to supply current to both of these socket interiors, as will be readily understood by those skilled in the art, the terminal block 44 being formed with an outer shell 51 containing wax, represented at 52, for holding the wires 47, 48, 49 and 50 rigidly in place, and also being provided with a cover section at one end, as represented at 53, the terminal block 44 being shown as of the type involving switch mechanism operated through the medium of the pull-chain 54 for controlling the flow of current to the socket interiors referred to. 105

In the particular arrangement shown the sockets may be wired to the terminal switch mechanism 44 before the assembly thereof with the housing structure 20, and these parts then assembled by introducing the terminal switch mechanism 44 into the ring-shaped member 22, the wires leading to the socket interiors being positioned in the bores 33 through the open sides 34 thereof, whereupon the cap plates 24 and 25 are applied to the ring member 22 to the position stated above and the portions 38 of the shells 37

telescoped with the bosses 28 and 29 to a position in which the portions 38 overlap the lugs 26, whereupon the set-screws 41 are turned to extend at their inner ends into the 5 grooves 30 in the bosses 28 and 29, the lead wires extending upwardly through the pipe 19 and boss 21 of the housing 20 being attached to the terminals 45 and 46 before the cap plates 24 and 25 are positioned as stated. 10 The device as shown also provides for the securing to the upright portion of the structure, of a lamp shade, the same being securable at different elevations. This is effected in the particular structure shown by the provision of a threaded rod 55 which screws into the upper boss 23 and carries two discs 56 and 57 threaded thereon, the upper end of the rod 55 being shown as provided with an ornamental section 58. By 15 virtue of the adaptability of the rod 55 to adjustment up and down on the housing 20 and the adaptability of the discs 56 and 57 to independent adjustment on the rod 55, the structure is adapted to support shades 20 at different elevations relative to the housing 20 and in a manner to present an ornamental appearance.

By providing the hollow bosses 21 and 23 the structure may be assembled with the 25 supporting structure, shown in the drawings as an upright, either in the position shown, or in inverted position, or wires may be led in through both of the bosses 21 and 23 as desired.

30 While the structure is shown as involving its support from a stand, it will be readily understood that it may be embodied in a chandelier, in which case the upper boss would connect with the part depending from the ceiling and supporting the fixture and the shade-holding means, if used, would be connected with the lower boss 21.

The structure shown in Figs. 13 to 18, 35 inclusive, involves a modification of the structure shown in the preceding figures whereby more than two of these socket members 36 may be rotatably supported on the central housing member. In the construction now being described this housing member, represented generally at 59, is formed of a lower hollow section 60 and an upper hollow section 61, the lower section 60 containing a boss 62 opening into the interior of the housing and corresponding with the boss 21 of the preceding figures and the upper section 61 being provided with a boss 62 opening into the interior of the housing and corresponding with the boss 23. The lower housing section 60 is provided with outwardly-extending bosses 64 which extend substantially horizontally, and are shown as radiating from the center of the housing, in the particular construction shown four of these bosses being provided and forming 40 journaling supports for four lamp-receiving

socket structures represented at 65 and corresponding with the hereinbefore described socket structures 36, the laterally-extending portions of these socket structures being represented at 66 and adapted to telescope with 70 the bosses 64 on which they are rotatable, the bosses 64 containing circumferentially disposed grooves 67 terminating in shoulders 68 and 69, and the upper portions of these bosses being slotted throughout their length, 75 as represented at 70, these slotted portions opening into the interior of the housing. The upper housing section 61 which telescopes with the wall of the section 60 at the open end of the latter, is provided with 80 radially-extending lugs 71 which, when the section 61 is assembled with the section 60, extends into the slots 70 in the section 60. The portions 66 of the socket member 65 upon being applied to telescoping position as 85 shown in Figs. 13, 14 and 18, overlap the lugs 71, thereby holding the sections 60 and 61 together to form the housing structure, the side wall of the section 61 at the open end of this section, being recessed as represented at 72 to straddle the bosses 64. The 90 socket portions 65 are provided with set-screws, represented at 73, extending at their inner ends into the groove 67 and functioning as explained of the set-screws 41 of the preceding figures.

In this construction the same shade-secur- 95 ing means are provided as explained of the ing construction in the preceding figures, the same numerals being applied to similar parts 100 which are carried by the upper housing section 61 instead of the substantially vertically disposed ring member 22 of the preceding figures.

It will be noted that the construction of 105 Figures 13 to 18 inclusive permits, when the housing section 61 is removed, the assembly with the section 60 of the terminal switch block corresponding with the block 44 of the preceding figures, and the wires leading therefrom into the socket interiors located in the socket portions 65, into the section 60, in assembled condition, inasmuch as the bosses 64 contain the slots 70, the pull-chain for actuating the switch referred 110 to being represented at 75 and operating in a chain-guide 76 in accordance with common practice.

115 It will be noted that in both of the constructions described, the socket portions are rotatably mounted on the central housing member and may be rotatably adjusted thereon to cause these sockets and the bulbs positioned therein, to extend into different angular positions, as desired.

Furthermore it will be noted that a structure embodying my invention may be constructed very economically, is simple of construction and presents a highly ornamental 120 appearance.

The set-screws 41 and 73 and 74 as provided may also serve the purpose, by screwing them to engage at their inner ends with the bosses 28, 29 and 70, of holding the 5 sockets in any position to which they are adjusted on these bosses.

While I have illustrated and described two embodiments of my invention, I do not wish to be understood as intending to limit 10 it thereby, as the same may be variously modified and altered, and the invention embodied in other forms, without departing from the spirit of my invention.

What I claim as new, and desire to secure 15 by Letters Patent, is:

1. In an electric-socket-equipped structure, the combination of a hollow supporting member formed of sections, one of said sections presenting a boss containing a recess in its outer surface, and the other of said sections having a lug which extends into said recess and an electric-bulb-receiving socket rotatable on said boss and overlapping said lug.

2. In an electric-socket-equipped structure, the combination of a hollow supporting member formed of sections, an electric-bulb-receiving socket rotatably mounted on said member and having a portion engaging said sections and releasably holding them together, said mounting involving a boss on said member with which said socket is telescoped and containing a groove in a plane at an angle to the axis of said boss, 30 and means on said socket and extending into said groove for holding said socket and boss in telescoped condition.

3. In an electric-socket-equipped structure, the combination of a hollow supporting member formed of a section open at its opposite ends and sections at the opposite ends of said first-referred-to section, and an electric-bulb-receiving socket mounted on said member and adjustable thereon for movement of the socket into different angular positions, and having a portion engaging said sections and releasably holding them together.

4. In an electric-socket-equipped structure, the combination of a hollow supporting member formed of a section open at its opposite ends and provided with a laterally-extending hollow boss, and sections at the opposite ends of said first-referred-to section, and an electric-bulb-receiving socket mounted on said boss and rotatably adjustable thereon for movement of the socket into different angular positions, and having a portion engaging said sections and releasably holding them together.

5. In an electric-socket-equipped structure, the combination of a hollow supporting member formed of sections, an electric-bulb-equipped socket mounted on said member to be adjustable thereon for movement

into different angular positions, and switch mechanism located in said member and electrically connected with said socket, said member containing an opening therethrough for the wires leading from said socket to said switch mechanism, said member being so formed as to permit the wires connected with said socket and with said switch mechanism to be introduced into said opening through the side wall of the opening and 70 said switch mechanism to be introduced into said member.

6. In an electric-socket-equipped structure, the combination of a hollow supporting member formed of sections having open sides, one of said sections being provided with a hollow boss, said boss being slotted throughout its length, an electric-bulb-receiving socket mounted on said boss and switch mechanism in said member, whereby, when the socket and switch mechanism are wired together and said sections are disassembled, the wires may be introduced into said boss through the slots therein and the switch mechanism into the interior of said member through the open side of one of said sections.

7. In an electric-socket-equipped structure, the combination of a hollow supporting member formed of sections having open sides and provided with hollow bosses, the side walls of the openings through said bosses being slotted throughout their length, electric-bulb-receiving sockets mounted on said bosses, and switch mechanism in said member, whereby, when the sockets and switch mechanism are wired together and said sections are disassembled, the wires may be introduced into said bosses through the slots in said bosses and the switch mechanism into the interior of said member through the open side of said section.

8. In an electric-socket-equipped structure, the combination of a hollow supporting member formed of sections, an electric-bulb-receiving socket having a portion engaging said sections and releasably holding them together, the mounting of said socket on said member being at a boss on the latter, and a set-screw operatively engaging said socket and boss.

9. In an electric-socket-equipped structure, the combination of a hollow supporting member formed of sections, an electric-bulb-receiving socket having a portion engaging said sections and releasably holding them together, said member being provided with a boss having a recessed portion and the mounting of said socket on the member being at said boss, and a set-screw extending through a portion of said socket and extending at its inner end into said recessed portion.

10. In an electric-socket-equipped structure, the combination of a hollow support-

ing member formed of sections, one of said sections presenting a boss containing a recess in its outer surface, and the other of said sections having a lug which extends into said recess and an electric-bulb-receiving socket on said boss and overlapping said lug.

11. In an electric-socket-equipped structure, the combination of a hollow supporting member formed of sections, an electric-bulb-receiving socket having a portion engaging said sections and releasably holding them together, said member being formed with a boss containing a groove in a plane at an angle to the axis of said boss, the

mounting of said socket on said member being at said boss, and means on said socket and extending into said groove for holding said socket and boss in telescoped relation.

12. In an electric-socket-equipped structure, the combination of a hollow supporting member formed of a section open at its opposite ends and sections at the opposite ends of said first-referred-to section, and an electric-bulb-receiving socket mounted on said member, said socket having a portion engaging said sections and releasably holding them together.

MAX HERSKOVITZ.
